UNITED STATES PATENT OFFICE.

CLAUDE A. RITTER, OF COVINGTON, KENTUCKY.

DESIGN FOR A COLLAR.

SPECIFICATION forming part of **Design No. 25,539, dated May 19, 1896.**

Application filed March 13, 1896. Serial No. 583,129. Term of patent 3½ years.

To all whom it may concern:

Be it known that I, CLAUDE A. RITTER, a citizen of the United States, residing at Covington, in the county of Kenton and State of Kentucky, have invented and produced a new and original Design for Collars; and I do hereby declare the following to be a full, clear, and exact description of the same, reference being had to the accompanying drawings, forming a part thereof.

Figure 1 of the drawings is a perspective view. Fig. 2 is a plan view of the ends, the central portion of the collar being broken away, the dotted line showing where the points of the collar are turned over.

The design consists of a novel and orna-

mental configuration given to the turned-over points of a collar. The edges of the collar-points are shaped in curves, and the two curved edges terminate in a point, as shown in the drawings.

What I claim, and desire to secure by Letters Patent, is—

The design for collars substantially as shown and described.

In testimony whereof I affix my signature in presence of two witnesses.

CLAUDE A. RITTER.

Witnesses:

JESSE R. RITTER,
HENRY MONVESSEL.
